UNITED STATES PATENT OFFICE.

LORENZO LITTLE CHRISTIAN, OF EUREKA SPRINGS, MISSISSIPPI.

DESIGN FOR A PLOW-HANDLE OR GRIP.

SPECIFICATION forming part of Design No. 26,444, dated December 22, 1896.

Application filed November 19, 1896. Serial No. 612,769. Term of patent 7 years.

To all whom it may concern:

Be it known that I, LORENZO LITTLE CHRISTIAN, a citizen of the United States, residing at Eureka Springs, in the county of Panola 5 and State of Mississippi, have invented and produced a certain new and original Design for Plow-Handles; and I do declare the following to be a full, clear, and exact description of the invention, such as will enable others skilled in the art to which it appertains to 10 make and use the same.

My invention relates to a hand-grip for plows, cultivators, and similar agricultural implements.

15 It relates to the entire configuration of the grip, as shown in the drawing.

My invention relates particularly to the hand-grip as illustrated in the accompanying drawing, in which the figure is a perspective 20 representation of a hand-grip for plows and the like, embodying my design.

The leading features of my design appear in the following description.

1 represents a rectangular socket the forward 25 sides of which are scalloped at 2 2, as shown, while the top and bottom ears 3 and 4 are curved inwardly at 5 5, and their outer beveled ends terminate in approximately semicircular curves 6 6, in the center of each of which is a vertical orifice 7. 30

The rear end of the socket 1 extends backwardly in a quadrilateral curve 8, having a smooth central rib 10 along its under side. The side of the curved quadrants is "checked," as shown, and an ornamental four-pointed 35 star 12 appears on each side. The entire hand-grip is cast in one piece.

Having thus fully described my design, what I claim as new and useful, and desire to secure by Letters Patent of the United States, 40 is--

The design for a hand-grip for agricultural implements, substantially as herein shown and described.

In testimony whereof I hereunto affix my 45 signature in presence of two witnesses.

LORENZO LITTLE CHRISTIAN.
